CLAIM

The ornamental design for a sculptured symmetric bottle, as shown and described.

DESCRIPTION

FIG. 1 is a perspective view of the sculptured symmetric bottle;

FIG. 2 is a front elevational view thereof;
FIG. 3 is a side elevational view as seen from the left hand side of FIG. 2;

FIG. 4 is a side elevational view as seen from the right hand side of FIG. 2;

FIG. 5 is a rear elevational view thereof;

FIG. 6 is a top plan view thereof; and,

FIG. 7 is a bottom plan view thereof.
